UNITED STATES PATENT OFFICE.

BEST AVAILABLE COPY

CHARLES R. INGHAM, OF SUFFERN, NEW YORK, ASSIGNOR TO AMERICAN
TURBINE ENGINE COMPANY, OF NEW YORK, N.Y., A CORPORATION OF
NEW YORK.

TURBINE-ENGINE.

SPECIFICATION forming part of Letters Patent No. 716,047, dated December 16, 1902.

Application filed March 25, 1902. Serial No. 99,867. (No model.)

To all whom it may concern:

Be it known that I, CHARLES R. INGHAM, a citizen of the United States, residing at Suffern, Rockland county, and State of New York, have invented certain new and useful Improvements in Turbine-Engines, of which the following is a specification sufficient to enable others skilled in the art to which the invention appertains to make and use the same.

10 My improvements relate to turbine steam-engines.

As heretofore constructed turbine-engines have been operated by the kinetic energy of steam acting upon radially-inclined surfaces 15 upon the periphery of the turbine in contradistinction to the utilization of the static expansive force of the steam, as in the ordinary reciprocating steam-engine. Furthermore, as heretofore constructed turbine steam-engines have been arranged so that the line of 20 action of the steam has been parallel to the axes of the turbine.

My invention consists in so constructing a turbine - engine that the static expansive 25 force of the steam is utilized as well as the kinetic energy thereof and in applying the steam at right angles to the axis of the turbine, as hereinafter set forth.

My invention also includes special features 30 of construction and arrangement hereinafter described and claimed specifically.

In the accompanying drawings, Figure 1 is an end elevation, on a small scale, of my improved turbine-engine. Fig. 2 is a central 35 longitudinal sectional elevation of the same. Fig. 3 is a transverse section upon plane of line 3 3, Fig. 2. Fig. 4 is a transverse section upon plane of line 4 4, Fig. 2. Fig. 5 is a partial section upon plane of line 5 5, Fig. 40 2. Fig. 6 is a transverse section upon plane of line 6 6, Fig. 2; Fig. 7, an elevation of the port-ring removed from the casing. Fig. 8 is a section taken upon plane of line 8 8, Fig. 2; Fig. 9, a partial section taken upon plane 45 of line 9 9, Fig. 8. Fig. 10 is a view similar to Fig. 9 of the opposite end of the turbine. Fig. 11 is a diagrammatic view showing the relative arrangement of the inlet and discharge ports.

50 In the accompanying drawings I have shown operative parts essential in carrying out my invention practically, all minor de-

tails being omitted; but I do not confine myself to the identical form and structure shown, since various modifications and mechanical 55 expedients may be resorted to without departing from the spirit and intent of my invention.

My turbine consists, essentially, of a rotatable center or hub A, formed with two or more series of annular peripheral steam-buckets, the buckets in each succeeding set or ring being larger in area than the buckets in the preceding one. Thus in the accompanying drawings two series A' A² A³ and a' a² a³ 60 of annular rows of steam-buckets are shown, the inner sets A' a' being the smaller and the buckets A² a² being intermediate in size as well as position between the buckets A' a' and the buckets A³ a³. Any desired number 65 of annular rows of buckets may be included in a series, as may be found most expedient, provided that there is a gradual progression in area to admit of the successive expansions of steam. In order to attain a perfectly-balanced engine in which there will be no end thrust in either direction, I prefer to arrange 70 the steam-buckets in two series, as shown, starting from or near the center, the several annular sets or rows of buckets being arranged successively, according to area, in opposite directions. It will be seen that there 75 is no communication through the rotatable hub A itself and the several rows of buckets. Each annular row and each bucket is 80 independent of all the others. Steam is admitted into the steam-buckets through inlet-ports I' I² I³ i' i² i³, formed in the port-cylinder R. These inlet-ports I' I² I³ i' i² i³ 85 are preferably arranged tangentially to the 90 periphery of the rotatable center or turbine A, and there are preferably as many of them as there are steam-buckets in the annular rows to which they are opposed. A corresponding series of discharge-ports D' D² d' d² 95 are also arranged in the port-cylinder R to conduct the steam from one set or row of steam-buckets to the next succeeding set. These discharge-ports extend obliquely 100 through the port-ring R at an angle with relation to the tangential inlet-ports referred to, so as to conduct the steam from one set of steam-buckets to the next succeeding set, as indicated by dotted lines in Fig. 2. Follow-

ing the arrangement shown in the drawings, by way of illustration, steam is admitted through a conduit S , which opens into a groove s , having two spiral branches $s' s^2$, which 5 communicate, respectively, with the first series of steam-pockets $E' e'$. This will be understood by reference to Figs. 3 and 7 and forms a simple, convenient, and advantageous arrangement, although not absolutely essential 10 to the successful operation of the machine, since the grooves $s' s^2$ may be supplied independently, if desired.

$E' E^2 E^3 e' e^2 e^3$ represent a series of expansion-pockets formed with radial walls or abutments e , which perform a function equivalent 15 to that of cylinder-heads in reciprocating engines in that they each afford a stationary resisting-surface against which the expansive force of the steam may be exerted through 20 the inlet-ports $I' I^2 I^3 i' i^2 i^3$ and against the opposed surfaces a of one of the turbine-buckets, each of which of said opposed radial surfaces a is thus made to perform the function 25 of a piston in a reciprocating engine.

It is to be understood that the inlet-ports $I' I^2 I^3 i' i^2 i^3$, and discharge-ports $D' D^2 d' d^2$, steam-pockets $E' E^2 E^3 e' e^2 e^3$, and steam-buckets $A' A^2 A^3 a' a^2 a^3$ increase progressively in size from first to last in proportion 30 to the successive expansion of steam to be effected as the steam passes through the apparatus according to well-known rules governing multiple-expansion engines, and I do not confine myself to the relative sizes and 35 portions shown in the drawings.

Having thus described the essential features of my improved turbine, the operation thereof may be stated, as follows: Steam entering at high pressure into the grooves $s' s^2$, 40 either directly or through the spiral groove s , as before stated, is injected forcibly and simultaneously into all the buckets in the series $A' a'$ through the first series of inner ports $I' i'$, impinging against the radial surfaces a of said 45 buckets $A' a'$, and then escaping through the oblique discharge-ports $D' d'$ into the next succeeding series of expansion-pockets $E^2 e^2$, from which it passes through the inlet-ports $I^2 i^2$ into the row of buckets $A^2 a^2$, to escape from 50 them in turn through the succeeding series of discharge-ports $D^2 d^2$ into the third series of expansion-pockets $E^3 e^3$ and through the succeeding rows of tangential inlet-ports $I^3 i^3$ into the rows of turbine-buckets $A^3 a^3$, and 55 so on for as many series of steam-buckets as may be provided in the turbine, finally escaping through the series of discharge-ports $D^8 d^8$ into the discharge-chambers $D^4 d^4$ at either end of the engine. It will thus be seen 60 that I am enabled to attain all the advantages of multiple expansion in a rotary or turbine engine and that the number of expansions may be extended indefinitely by increasing the series of steam-buckets with the 65 necessary ports, &c., included. I also retain all the advantages of the initial impact or kinetic force of the steam, by which alone tur-

bines have heretofore been operated. Furthermore, both the kinetic and expansive force of the steam is exerted at right angles, or substantially so, to the axes of the turbine in contradistinction to the old method of applying the force of the steam parallel to the axis. The advantages thus attained both in simplicity and efficiency are obvious, the impact and expansion of the steam being exerted under the most advantageous conditions, so that all the power inherent in the steam is fully imparted to the turbine in a relatively short period—that is to say, a given degree of power and speed 80 is attained by my improved construction with greater economy of space and apparatus. In fact, the simplicity of the apparatus is in marked contrast to all turbines as heretofore constructed, the only operative part being the 85 rotatable center, in which the steam-buckets may be said to be sunk. When the delicate and expensive character of the usual steam-blades projecting from the periphery of the ordinary turbine is considered, it will be seen 90 that my structure is not only much cheaper as to first cost, but also as to maintenance.

As before stated, the structure herein shown is by way of illustration only and may be modified to suit requirements. For instance, 95 I have herein shown the inlet-ports and discharge-ports as formed in the cylindrical port-ring R , which is forced into the casing B and becomes practically integral therewith.

For convenience of construction I preferably, though not necessarily, make the casing B of a series of annular sections $B' B^2 B^3$ and $b' b^2 b^3$, containing the steam-pockets $E' E^2 E^3$ and $e' e^2 e^3$, interposed between plain annular partitions $C' C^2 C^3 c' c^2 c^3$, in addition to the 105 central partition C^4 . These sections and partitions are bolted or otherwise secured rigidly together. The rotatable center or hub A may in like manner be formed of a series of sections in which the steam-buckets are formed, 110 said sections being separated by a series of annular partitions, as indicated in the drawings.

It is obvious that a single series of buckets $A' A^2 A^3$ or more, extending from one extremity of the rotatable center A toward the other, may be used, if desired; but I prefer to use a duplex series, as shown, for the purpose of avoiding end thrust and attaining a perfectly-balanced turbine.

It will be seen that by my invention I am 120 enabled to provide for any number of multiple expansions, each ring or series of buckets, with its inlet and discharge ports, &c., constituting practically an independent expansion-engine. Thus in the drawings I attain 125 the effect of two triple-expansion rotary engines incorporated in a single rotatable center or turbine.

By reference to Fig. 11 it will be seen that the inlet and discharge ports are alternately 130 opened and closed as the center rotates, thus insuring successive expansions of the steam as it passes from the steam-pockets in the casing into the steam-buckets in the center.

What I claim as my invention, and desire to secure by Letters Patent, is—

1. In a turbine-engine, the combination with a rotatable center formed with a plurality of annular rows of steam-buckets, each annular row and each bucket being independent of all the others, and each succeeding row of larger area than the preceding row, said buckets being arranged in series and disposed successively according to area in opposite directions, of a casing formed with annular steam-buckets and tangential inlets for conducting steam successively from one annular row of buckets in said center to another, as set forth.

2. In a turbine-engine, the combination with a rotatable center formed with a plurality of annular rows of steam-buckets, each annular row and each bucket being independent of all the others, and each succeeding row of larger area than the preceding row, said buckets being arranged in series and disposed successively according to area in opposite directions, of a casing formed with annular steam-buckets and tangential inlets for conducting steam successively from one annular row of buckets in said center to another, and discharge-ports for transferring steam from the primary rows of turbine-buckets in said center to the next succeeding rows, as set forth.

3. In a steam-turbine the combination of the rotatable center formed with a plurality of annular rows of steam-buckets, the stationary casing formed with a corresponding series of annular steam-pockets, tangential inlets admitting steam to the primary rows of steam-buckets, discharge-ports for conducting the steam from said primary rows of steam-buckets to the second annular series of steam-pockets, inlet-ports for admitting steam from the secondary rows of steam-pockets to the secondary rows of steam-buckets and ports for discharging the steam from said secondary rows of buckets, substantially as set forth.

4. In a steam-turbine the combination of the rotatable center A, formed with a plurality of rows of annular steam-buckets of different area, the stationary casing formed with a corresponding series of annular steam-pockets a series of inlet-ports corresponding in number to the series of steam-buckets in the primary rows and with a series of discharge-ports of like number for conducting the steam from the primary rows of steam-buckets to the next succeeding rows of steam-buckets, substantially as set forth.

5. In a steam-turbine the combination of the rotatable center, formed with a plurality of annular rows of steam-buckets, the stationary casing formed with an annular steam chamber or groove having a series of inlet-ports corresponding in number to the series of steam-buckets in the primary rows, a series of discharge-ports of like number for conducting the steam to a secondary annular series of steam-pockets, a series of inlets corre-

sponding in number to the steam-buckets in the secondary rows and a series of discharge-ports of like number for admitting the escape of the steam from said secondary rows of steam-buckets, substantially as set forth.

6. In a steam-turbine the combination of the rotatable center formed with a plurality of rows of steam-buckets and the stationary casing formed with an annular series of steam-buckets having inlet-ports equal in number to the number of steam-buckets in the primary rows with an equal number of discharge-ports for conducting steam from said primary rows of buckets, with a secondary series of steam-pockets for receiving the steam from said discharge-ports, with secondary rows of inlet-ports equal in number to and for conducting the steam to secondary annular rows of steam-buckets, and with a corresponding number of discharge-ports for conducting the steam from said rows of steam-buckets, substantially as set forth.

7. In a steam-turbine the combination of the rotatable center formed with a plurality of annular rows of steam-buckets, and the stationary casing formed with a corresponding series of steam-pockets, the primary rows of which are connected by a series of inlet-ports with the primary annular rows of steam-buckets and the succeeding series of which are connected, respectively by discharge-inlets with the preceding row of steam-buckets and by inlet-ports with the succeeding row of steam-buckets substantially as set forth.

8. In a steam-turbine the combination of a rotatable center, formed with a plurality of annular rows of steam-buckets arranged in two series, each series consisting of two or more annular rows of steam-buckets of different area, and a stationary casing formed with corresponding series of steam-pockets, with inlets for admitting steam respectively to each of the buckets in each series and with discharge and inlet ports for transferring the steam from the steam-pockets to the steam-buckets, substantially as set forth.

9. In a steam-turbine the combination with a rotatable center formed with a plurality of rows of annular steam-buckets arranged in two series substantially as set forth, and a casing formed with a spiral steam-inlet passage opening into annular steam-passages having inlet-ports for conducting the steam from said annular steam-spaces into the primary rows of steam-buckets in each series of steam-buckets and with discharge and inlet ports for transmitting the steam from said primary rows of steam-buckets to succeeding rows, substantially as herein set forth.

10. In a steam-turbine the combination with the rotatable center formed with a plurality of steam-buckets arranged in two series substantially as set forth, and the stationary casing formed with two annular steam-spaces having inlet-ports corresponding in number to the steam-pockets in the primary rows in each series, formed with corresponding num-

ber of discharge-ports for conducting steam from said primary rows of steam-buckets to steam-pockets with inlet-ports corresponding in number to the buckets in the secondary 5 annular rows of steam-buckets in the rotatable center and with a corresponding number of discharge-ports for conducting the steam from the secondary rows of steam-buckets to secondary steam-pockets for the purpose and substantially in the manner set forth.

11. In a steam-turbine the combination of the rotatable center formed with steam-buckets having radial surfaces and arranged in series and disposed successively according to 15 area in opposite directions, and a stationary casing formed with inlet-ports tangential to the rotatable center, and with a corresponding number of discharge-ports and steam-pockets, substantially in the manner set 20 forth.

12. In a steam-turbine the combination with the rotatable center formed with radial surfaces for receiving the impact of the steam and arranged in series and disposed successively according to area in opposite directions each row and each bucket being independent of all the others, of the stationary casing formed with the inlet-ports tangential to 25 said rotatable center, and with expansion-30 pockets formed with surfaces which are sub-

stantially radial to the rotatable center, for the purpose and substantially in the manner set forth.

13. In a steam-turbine the combination with the rotatable center formed with series steam-buckets having radial impact-surfaces, of the stationary casing formed with a corresponding number of inlet-ports tangential to the rotatable center, with a corresponding number of steam-pockets and a corresponding number 35 of discharge-ports, the steam-pockets being arranged to receive the steam from one series of steam-buckets and transfer it to the next succeeding series, substantially as set forth.

14. The combination of the rotatable center consisting of a series of sections formed with steam-buckets, and annular partitions interposed between said sections, the port-cylinder formed with the inlet and discharge 45 ports, and the casing consisting of a series of sections formed with steam-pockets, and annular partitions interposed between said sections, substantially as and for the purpose set forth.

CHARLES R. INGHAM.
